Primary Examiner — Leanne Was-Englehart*Assistant Examiner* — Alison Davis(74) *Attorney, Agent, or Firm* — Birch, Stewart, Kolasch & Birch, LLP(57) **CLAIM**

The ornamental design for a television receiver as shown and described.

DESCRIPTION

1. Television receiver

1.1 : Front perspective

1.2 : Back perspective

1.3 : Front

1.4 : Back

1.5 : Left

1.6 : Top

1.7 : Bottom

The broken lines indicate portions of the television receiver that form no part of the claimed design; the right side view is omitted because it is a mirror image of the left side view. The portions of the design shown in the color gray in Reproductions 1.4-1.6 illustrate portions of the television receiver that form no part of the claimed design.
